PUNCHING AND REINFORCING DEVICE FOR
SHEET MATERIAL

Carman Lo Forese, Brooklyn, N. Y.

Application January 14, 1948, Serial No. 2,184

2 Claims. (Cl. 93—1)

1

This invention relates to devices for punching holes into a sheet material and also to secure a reinforcing ring therearound, like in a loose leaf, drawing, map, etc., to be suspended or placed on pins, and has for its main object to provide a device of this type, which will be more efficient, more practical, and more convenient in use, than devices heretofore proposed for this purpose.

Another object of this invention is to provide a device of the character mentioned, which can be changed to a plain punching device without the reinforcing feature, if desired.

Still another object of this invention is to provide a device of the mentioned character, which will have a large amount of reinforcing material for adhesion stored therein, whereby it will be adapted for a long use without refilling.

Still a further object of this invention is to provide a novel method and means for moistening an object, like a disk of sheet material for adhesion, in a safe and exact manner.

Still a further object of this invention is to provide a device of all the mentioned improvements and others as will be pointed out, which will be simple, compact, and adapted for easy manual operation, and will be portable.

Other objects of my invention will be apparent as the specification of the same proceeds, or will be pointed out therein, and, among others, I may mention: to provide a device of the indicated character, type, and improvements, which will be simple in construction, which may punch the material in a dry state thereby insuring a more exact clean cut, and wherein the refilling, inspecting, repairing, or replacing of parts may be done easily and conveniently.

In the drawings forming a part of this specification and accompanying the same:

Fig. 1 is a semi-diagrammatical elevational view of my device;

Fig. 2 is a plan view, and

Fig. 3 is a front view thereof;

Fig. 4 is a sectional view of the front part of my device, on a larger scale than the earlier figures, the section being taken on the line 4—4 of Fig. 2;

Fig. 5 is a partly sectional plan view of said front part of the device, the section generally being as indicated on the line 5—5 in Fig. 4;

Fig. 6 is a plan view of a removable detail embodying the moistening device of my invention, and

Figs. 7 and 8 are sectional views thereof on the lines 7—7 and 8—8 of Fig. 6, respectively, while

Fig. 9 is a rear view of the same;

Fig. 10 is another detail showing a ratchet device used for propelling an adhesive tape in my invention,

2

Fig. 11 is a sectional view, generally on the line 11—11 of Fig. 10;

Figs. 12 and 13 are fragmentary elevational and sectional views, respectively, showing the pivoted arrangement for a forked operating handle of my device, and the arrangement of a spiral spring adapted to return the same into its normal inoperative position;

Figs. 14 and 15 are sectional views showing the two phases in the operation of a yielding support for the sheet operated on;

Fig. 16 is a sectional detail of a limiting device for the stroke of the plunger in my invention, and

Fig. 17 is another sectional detail of an adjustable limit for the sheet to be worked on.

Figs. 18 and 19 are plan and sectional views, respectively, of a modification of my moistening device.

Referring now to the drawings, more in detail, by characters of reference, the numeral 30 indicates my novel sheet material punching and reinforcing device, in general, mainly being composed of a housing, indicated by the numeral 31, a swingable rear top portion 32 with a stationary operating handle 33, and an operating cylinder 34 in the upper front part thereof underneath which is provided a forwardly open space 35.

A forked pivoted operating handle 36 is secured on the housing, as will be more fully explained hereinafter, the forward ends thereof actuating a punching plunger 37.

A forwardly removable moistening member, generally indicated by the numeral 38, is arranged in the space 35, the top 39 thereof serving as a support for an adhesive reinforcing tape 40, while, underneath the same, the portion 41 of the housing carries a yieldable support 42 for the sheet 43 to be operated on.

As has been mentioned, my invention mainly aims to provide a novel, simple, compact, hand operated device, whereby a hole may be punched into a sheet material, like a loose leaf, drawing, a map to be suspended, etc., and, at the same time, my device will punch a reinforcing ring and secure it around said hole. I also aim to provide a device of this character which, by very simple adjustment thereof, will be adapted to be used as a punch without the reinforcing feature.

The housing 31 will have a generally horizontal rear portion 44, a part of which is said swingable rear cover 32 pivoted as at 45. Into said rear portion is set a roll 46 of the adhesive tape 40, in the embodiment shown it simply being dropped into the rear part of the housing, and being slidably and rotatably held between two pivot pins or short shafts 47 arranged in the side walls 48 of the housing, for the forwardly projecting front fork arms 36a of the

operating handle or lever 36. Through the front end of the arm 36a passes a horizontal pin 49 adapted to move in slots 36b in the arm 36a, said pin 49 being upwardly and downwardly slidable in slots 50 in the two sides of the front cylinder 34, the plunger 37 being secured on said pin, as at 51.

The front part of the removable moistening and support device 38 is hollow, as indicated at 52, and in the tape supporting portion 39 thereof a cylindrical hole 53 is provided, being identical in diameter with the inner diameter of the cylinder 34, or with the outer diameter of the plunger 37.

It will be seen that when the plunger is moved downwardly and arrives to the hole 53, its outer edge cooperating with the inner edge of said hole will act as a punch and will sever a disk of the diameter of said plunger from the tape 40.

Removable moistening and support member 38 (Figs. 1 and 6 to 9) has a water reservoir space 54 in the rear upper part thereof, which is continued in two forward branches 55 and two semi-circular forwardly closed pipes 56 are pivoted in the space 52, as at 57. The forward ends of the channel 55 will have communication with the interior of the semi-circular pipes 56, so that the water from the reservoir 54 and forward branches 55 may flow into said pipes, their pivots 57 sealed in a water tight manner.

In the embodiment shown, I provide a plurality of radially inwardly pointing bristles 58, in such a manner, that the liquid in the semi-circular tubes may seep from them along the bristles 58, and it will be seen that after the plunger 37 punches the mentioned disk out of the material of the tape 40, and it will continue its downward movement, as will be explained presently, the disk will press on the bristles 58 and through said bristles it will turn the semi-circular pipes 56 downwardly on their pivots 57, as indicated in Fig. 7, said bristles sweeping along the lower surface of said disk, wetting the same, and finally being folded along the sides of the opening 52 permitting a further downward travel of the disk punched from the tape 40, the lower surface of which now has been moistened.

Upon still a further downward travel of the plunger 37, the disk will arrive on the sheet 43 to be operated on, and through pressure of the plunger will be secured thereon, since the tape 40 will be made of such material, that upon moistening its lower surface, it will become adhesive.

The support 42 for the sheet 43 is upwardly and downwardly slidable, being arranged on pins 59 normally upwardly urged by the springs 60. Plunger 37 will have a bottom wall 61 and an aperture 62 provided therein, while the lower supporting portion of the housing will have an upward cutting pin 63 closely, but slidably, fitting into the hole 62, so that when the plunger arrives on the sheet 43 to be operated on, and continues its downward movement, the upward pin 63 in cooperation with the hole 62 in the bottom of the plunger, will punch a hole of the size of said pin 63 in the sheet 43 operated on, as well as in the reinforcing tape disk secured thereon, as will be understood.

The normal position of the support 42 for the sheet 43, is indicated in Fig. 14, and its position at said perforating operation in Fig. 15.

To execute the said downward movement of the plunger 37, the operator simply grips the operating handle 36 and the stationary handle

33, and swings the first one towards the second one, as indicated by the arrow 64 in Fig. 1, the handle 36 being pivoted as at 47 by its fork arms 36a at both sides of the housing, the forward ends of said arms 36a will move downwardly, arrow 65, and will cause the plunger 37 to execute the movements described hereinbefore.

As also has been mentioned, arms 36a are secured on short shafts 47 in the two sides 48 of the housing 11, and a spiral spring 66 is secured at one end to shaft 47, and at the other end on the respective side wall 48, as indicated at 67 (Figs. 4, 12 and 13). When the handles 33 and 36 are closed upon one another, the plunger 37 will travel downwardly, as has been explained, and when said handles are released, the springs 66 will return the arms 36a into their upper inoperative positions.

The feeding of the tape 40 is executed by a friction roller 68, which preferably may be made of hard rubber, and which, under pressure, frictionally and strongly engages the tape 40 at their meeting, as indicated at 69.

A ratchet device, generally indicated by the numeral 70 (Figs. 4, 5, 10 and 11) is provided to intermittently turn the friction roller 68 in the direction of arrow 71, and thereby cause a forward propelling of the tape 40. The ratchet device 70 is operated from one of the arms 36a in the embodiment shown being a left side arm of the device when viewed from the front, and it will be seen that a short transverse pin 72 is provided over the said arm 36a, upwardly and downwardly travelling in a slot 73 in the respective side wall 48. On the inner side of the pin 72, a link member 74 is pivotally secured thereon, the lower end of the same being pivotally attached as indicated at 72a, to a ratchet operating number 75, rotatable on the shaft 76 of the friction roller 68.

A toothed ratchet wheel 77 is secured on the roller 68, and two dogs 78 are pivotally secured at the ends 72b and 72a of the rotatable member 75. A coil spring 79 is also secured to the end 72b of said member, while the other end of said spring is secured on the respective side wall 48, as at 80.

The use and operation of my device will be practically understood from the drawings and description thereof. However, I offer the following remarks to further explain the same:

When it is desired to use my device, the sheet 43 in which a reinforced hole is to be produced, will be placed in the lower forwardly open space 42a over the downwardly yieldable platform 42, whereupon the handles 33 and 36 will be gripped by the hand of the user and pressed on one another, which, of course, will cause the pivoted handle 36 to move closer to the stationary handle 33 (arrow 64), whereby the front fork arms 36a thereof will move in the opposite direction downwardly (arrow 65). This movement will cause the plunger 37 to pass downwardly and it first will sever a disk from the tape 40 of the size of the bottom of the plunger, the plunger carrying said disk further downwardly, whereupon it will engage the pivoted moistening members 56, pressing the under surface of the tape disk against their moistened bristles, but forcing said bristles out of the path of the plunger 37, as will be understood.

On a further travel, the plunger will press the moistened adhesive disk on the sheet 43 to be operated on, and on a still further travel of the plunger, the aperture 62 in its bottom in coopera-

tion with the upward pin 63 in the bottom of the housing, will punch a hole both, in the sheet worked upon, and in the disk secured thereon.

When the handles 33 and 36 are released, the spiral springs 66 will return the pivoted handle 36 into its original position, thereby withdrawing the plunger 36 into its original separating position, and the device is ready for a new punch and reinforcing operation.

It will be seen that on the return movement of the forward arm 36a in the embodiment shown in the drawings, link 14 will operate the propelling friction roller on the tape 40, and move the same with a desired predetermined amount, while, upon the downward operative movement of the arm, coil spring 79 will cause the ratchet device to idly move, so as to be prepared for the next turning movement for the friction roller 68.

As has been mentioned hereinbefore, the member 38 provides the support 39 for the tape 40 as well as the disk cutting die opening 53, and the moistening device with its reservoir, all in one single unit and removable, for which purpose it may have rectangular slots 82 in its side, and a corresponding lug in the two sides of the opening in the housing for the same, said unit 38 being in this manner inwardly and outwardly slidably, and, in this manner, the reservoir can be refilled when necessary, as well as the moistening device inspected, repaired, or adjusted, or, if necessary, exchanged.

In the rear of the space 42a of the support 42 for the sheet to be operated on, I arrange an adjustable limit device, generally indicated by the numeral 83. The device will have a rear elongated frame like portion 84, slideable on the respective outer side of the housing 31 of my device, and adapted to be secured in any of its positions by the set screw 85. The forward end of the frame 84 carries a limit proper arm 86 arranged transversely in the rear of the space 42a and support 42 for the sheet to be worked on. Obviously sheet 43 can be pushed inwardly as far as the limit 86 will permit, and the position of said limit may be set as allowed by the length of the frame 84.

Markings may be employed on the outside of the housing in the path of the frame 84, showing the distance of the hole to be punched in the sheet from its inner edge, so that the limit can be set as desired.

I also may employ a knife device, generally indicated by the numeral 87 in front of the opening 35 for the tape 40, and as the used tape is advanced out of its opening, its down hanging waste portion may be cut off by the use of the knife 87, as will be obvious and as indicated at 88.

My device may also be easily adjusted so as to cut out the reinforcing feature thereof and use it as a plain punching device. In many cases only this is needed. For this purpose I may employ an inwardly and outwardly moveable limit pin 89 in the upper front part of the housing. When it is desired to cut out the reinforcing disk portion of my device, said pin will be pushed inwardly as indicated by the dotted lines in Fig.

4. In such a position, it will not permit a return of the plunger 37 beyond this position, and thereby will stop the operation of the ratchet device and friction roller 68, so that no tape 40 will be fed in the path of the plunger 37, and the same will only operate in the last phase of its movement upon the sheet 43, punching a hole therein as defined by the pin 63 in the bottom of the 75

housing and the aperture 62 in the bottom of the plunger. A slot 90 may be provided in which an upward projection 91 of the pin 89 will ride, thereby providing a limit to the outward movement of the pin 89. The inward limit thereof will be provided by the head 92 of the same.

In Figs. 18 and 19 I show a modification of my moistening device proper. In Fig. 18 I show a plan view of one of the swinging semi-circular

10 tubes, the construction and use of it being identical to the semi-circular moistening tubes 56 described hereinbefore. In this embodiment, however, a piece of appropriate fabric 58a is placed over a semi-circular metal plate 93 instead of the formerly described bristles. The moisture from the semi-circular tube will seep through the fabric 58a, and the use and operation of the device, otherwise, is entirely identical to the one described hereinbefore.

15 Fig. 19 is a sectional view on the line 19-19 of Fig. 18.

What I claim as new and want to protect by Letters Patent of the United States, is:

1. In a punching and reinforcing device for sheet materials, a housing, a first handle secured at the rear of the housing and stationary therewith, a second handle projecting rearwardly from the housing and pivoted on the same, a hollow cylinder in the front part of the housing perpendicularly to said handles, a plunger in said hollow cylinder, means whereby said pivoted handle may move said plunger upwardly and downwardly, a roll of tape material in the rear of said housing, a first space in said housing rearwardly extending from the front thereof, a support for said tape in said space, a second space opening from the front of the housing rearwardly therein underneath said first space, a support in said second space for the sheet to be operated on, said support being adapted to be resiliently moved in a downward direction, an aperture in said first support through which said plunger may slide and thereby cut a disk of said tape, an aperture in said second support, a stationary pin projecting from the housing through said second aperture, an aperture in the bottom of the plunger adapted to slidably engage said pin and thereby punch a hole, both, in the tape disk, and in the sheet material, and yielding means in the aperture in the first support adapted to moisten the underside of the tape for an adhesive action.

2. In a device, as set forth in claim 1, said moistening means including a pivoted member adapted to engage the lower surface of the disk cut from the tape and slide therealong for better action, a spring device normally urging said moistening means into their upwardly original position, and means to conduct moistening liquid on to said pivoted member.

60 CARMAN LO FORESE.
